UNITED STATES PATENT OFFICE

132,461

DESIGN FOR AN AIRPLANE

Alfred J. Klose, Inglewood, Calif., assignor to
Vultee Aircraft, Inc., a corporation of Dela-
ware

Application May 5, 1941, Serial No. 100,788

Term of patent 7 years

To all whom it may concern:

Be it known that I, Alfred J. Klose, a citizen
of the United States, residing at Inglewood, in
the county of Los Angeles, and State of Califor-
nia, have invented a new, original, and orna-
mental Design for an Airplane, of which the fol-
lowing is specification, reference being had to
the accompanying drawing, forming a part
thereof.

In the drawing:

Figure 1 is a plan view of an airplane showing
my new design;

Figure 2 is a front elevational view of the air-
plane; and

Figure 3 is an enlarged side elevational view
of the airplane.

I claim:

The ornamental design for an airplane, sub-
stantially as shown.

ALFRED J. KLOSE.
